United States Patent Office.

W. A. CROCKER, OF NORFOLK, VIRGINIA.

Letters Patent No. 97,364, dated November 30, 1869.

IMPROVEMENT IN PEANUT-PICKER.

The Schedule referred to in these Letters Patent and making part of the same.

To all whom it may concern:

Be it known that I, W. A. CROCKER, of Norfolk, Norfolk county, State of Virginia, have invented a new and improved Peanut-Picker; and I do hereby declare that the following is a full, clear, and exact description thereof, which will enable others skilled in the art to make and use the same, reference being had to the accompanying drawing, forming part of this specification.

The object of this invention is to provide a simple and efficient machine for separating peanuts from the vines; also to separate them from the chaff, light and faulty peas, and to rub and scour the shells.

The invention comprises an arrangement in an enclosed case, through which the vines are supplied, at one end of an endless chain-carrier, composed of chains woven together diagonally, making large angular meshes, working between fixed screens, one above and the other below the upper portion of the chains.

Also, in combination with the above, a rotary spiked vine-discharger, a fanning-device, and a scouring-apparatus, all as hereinafter more fully specified.

Figure 1 represents a longitudinal sectional elevation of my improved machine, and

Figure 2 represents a top view, with a part of the case removed.

Similar letters of reference indicate corresponding parts.

A represents a long and broad case, supported upon a frame, B, within which an endless chain-carrier, C, composed of chains woven together diagonally, so as to form large angular meshes, works over the drums D, one at each end.

E is a permanent screen, with meshes of similar angular shape, arranged in the detachable cover, above the top of the chain-carrier, one end at the hopper F, where the vines are fed in, being considerably higher than the other, at G, where they are discharged, which is brought nearly down to the chain.

H is another permanent screen, supported on cross-bars I, below the said upper part of the chain-carrier.

The lower part of the carrier runs along the bottom K of the case, and over a discharge-space, M, at the end below the feeding-hopper, covered by a screen, L.

Below the said bottom K of the carrier-case is a fan-blower, S, arranged to impel a blast of air through the falling current of nuts, chaff, &c., at the passage

M, the inclined walls thereof being opened at N for the said blast.

After passing through this blast, by which the light matters are separated, the nuts are received upon an adjustable inclined chute, O, which delivers them into a circular screen of wire, P, permanently fixed, open at one end, and provided with a revolving reel, Q, of beater or scouring-arms, arranged spirally, so as to gradually convey the nuts to the said open end for discharge, at the same time that the rotation of the arms effects the scouring.

R represents a spiked cylinder, arranged under the chain-carrier, to insure the discharge of the vines, to prevent the return of those once acted upon to mix with the fresh supply and clog the machine.

The peanuts have long slender projecting stems generally suspended from the vines, and on being placed on the chain-carrier, will naturally fall through the meshes, and be scraped off by the action of the permanent screen below, while those projecting upward will encounter the upper permanent screen as the vines are carried along by the said carrier.

The carrier-drums may be set in action by any suitable arrangement of belts or other driving-machinery, and the scourer, fan, and discharger may be driven by belts from one of the chain-carrier drums.

The nuts which fall through the chain and screen H, upon the bottom K of the chain-case, are scraped off, by the returning part of the chain, into the passage M.

Having thus described my invention,

What I claim as new, and desire to secure by Letters Patent, is—

1. The combination, with the chain-carrier, constructed as described, of the permanent screens E and H, substantially as specified.
2. The combination, with the carrier and screens H and E, arranged as described, of the discharge-wheel A, substantially as specified.
3. The combination of the chain-carrier, screens E and H, and the scouring-reel Q, and permanent wire screen shell P thereof, substantially as specified.
4. The combination, with the carrier, screens E H, scouring-reel Q, and permanent screen P, of the fan-blower G, substantially as specified.
